UNITED STATES PATENT OFFICE

ALBIN E. JUBY, OF BORGER, TEXAS

BUILDING SET

Application filed June 15, 1929. Serial No. 371,187.

This invention relates to apparatus for constructing buildings of molded material such as cement and pertains particularly to a structure for forming blocks of material and for forming in set-up condition hollow wall structures.

The primary object of this invention is to provide a structure by the use of which a complete building may be set-up from the foundation to the roof including floor and ceiling joists and ceiling base built over false floor.

Another object of the invention is to provide a structure by which walls may be cast having air spaces extending therethrough to all parts and having inner and outer bodies bonded together by webs of the cement of which the wall is constructed, the areas between the inner and outer bodies and between the bonding webs forming spaces for the circulation of air.

Another object of the invention is to provide a collapsible wall form having inner and outer form walls and central or core walls with means for maintaining all of the walls in a predetermined relation for the formation of a cement wall of the character above described and further having the core walls transversely divided and so connected that a collapsing of the core form will take place when the elements of the structure are released from the fixed wall forming position to be set-up in another position.

Still another object of the invention is to provide an improved hollow brick or cast block forming structure having a collapsible central or core portion for facilitating the removal of the block from the form.

Other objects and advantages of the invention will become apparent as the description of the same proceeds and the invention will be best understood from a consideration of the following detailed description taken in connection with the accompanying drawings forming a part of the present invention with the understanding, however, that the invention is not confined to any strict conformity with the showing of the drawings but may be changed or modified so long as such changes or modifications mark

no material departure from the salient features of the invention as expressed in the appended claims.

In the drawings:—

Figure 1 is a view in plan of one of a plurality of block forms;

Figure 2 is a sectional view taken on the line 2—2 of Figure 1;

Figure 3 is a detail of the under side of one end of a cover for a block form;

Figure 4 is a sectional view taken on line 4—4 of Figure 2;

Figure 5 is a sectional view taken on the line 5—5 of Figure 1;

Figure 6 is a top plan view of a portion of the wall forming structure embodying a part of the present invention;

Figure 7 is a side elevational view of the structure shown in Figure 6;

Figure 8 is a sectional view taken on the line 8—8 of Figure 6;

Figure 9 is a detailed sectional view taken through the adjacent ends of a pair of cores, substantially upon the line 9—9 of Figure 6.

Figure 10 is a sectional view taken on the line 10—10 of Figure 8;

Figure 11 is a sectional view taken on the line 11—11 of Figure 6;

Figure 12 is a detailed sectional view of the joint between the walls of units of the structure.

Referring more particularly to the drawings wherein like numerals of reference indicate corresponding parts throughout the several views, the numeral 1 indicates generally the present hollow block or brick forming structure embodying a part of the present invention which structure, as shown, is designed for molding at one operation, a plurality of hollow blocks preferably 24" long, 8" wide and 10" high though, of course, I wish it to be understood that I do not want to be limited to the structure for forming blocks of this size only as it will be obvious that a brick of any size may be formed.

The brick casting form comprises a base 2 provided with longitudinally extending walls 3 which are spaced apart a distance equal to the length of the blocks, that is approximately 24". Running transversely of the longi-

tudinally extending walls 3 are transverse walls or partitions 4 which are spaced a distance equal to the width of the blocks, that is, approximately 8" apart thus forming the block spaces or chambers 5 in which the blocks are formed. In each of the spaces 5 there is set-up a collapsible core forming structure which comprises a rigid back wall 6 which extends lengthwise of the formed block, a shiftable forward wall 7 which is designed to move toward or away from the wall 6 and end walls 8.

As is shown, the four walls 6, 7 and 8 form a rectangular core and when set-up a block 15 is formed by filling the spaces between these walls and the partitions 4 and 5 surrounding them with the cement or other plastic material.

Each of the end walls 8 of the block core structure is turned at an angle as indicated at 9 and one of these angled ends of each end wall is hingedly connected as indicated at 10 to the adjacent end of the stationary wall 6. Each end of the shiftable wall 7 is also angled 25 as indicated at 11 and when the core is assembled for the formation of a block, the angled free end of each end wall is swung to position against the adjacent angled end of the shiftable wall so that the end walls maintain 30 the shiftable wall in spaced relation with respect to the fixed wall 6.

A spring 12, or if found desirable a rubber body may be used in this position, is stretched between the walls 6 and 7 so that when the walls 8 are swung in to collapse the block core the shiftable wall 7 will be drawn in also permitting the easy removal of the block.

Each of the block core structures is covered or closed by a top 13 upon the underface of 40 which at each corner there is secured a depending resilient arm or bracket 14 which frictionally engages the inner face of an angled corner of the core to maintain the top in position. It will thus be seen that with 45 a number of the cores set-up and each covered by a top 13, cement may be poured over the entire structure to fill all of the forms without danger of getting any of the material in the cores thereof.

50. In Figures 6 to 11 there is shown the structure provided for the casting or molding of building walls and other units of a building in set position. In this forming structure there are provided inner and outer form walls 15 and 16 respectively and center or core forms each indicated as a whole by the numeral 17 each of which comprises a pair of walls 18 which when set-up are arranged in spaced parallel relation with the inner and outer form walls in the manner shown.

These pairs of core walls 18 are formed at each end edge to extend obliquely of the formed wall, as indicated at 19 and are connected by the heavy resilient webs 20 which 65 are preferably constructed of rubber of suit-

able weight, these webs being secured to the core walls in any suitable manner.

In order to maintain the core walls 18 in the proper relative positions with respect to one another and with respect to the inner and outer form walls and to maintain the inner and outer form walls in the proper position, there are provided a number of holding devices each of which is here indicated generally by the numeral 21.

70 Each of these holding devices consists of a pair of beams 22 and 23 one of which, as for example the beam 22, is pivotally attached at one end, as at 24, to the other beam at a point inwardly of one end thereof, which end 75 for convenience in describing this device will be referred to as the forward end.

80 Each of these beams 22 and 23 of each holding member carries a pair of depending legs 25, which legs are preferably formed, as are 85 also the beams 22 and 23, of sheet iron. Each of the legs 25 is adjustably attached to its supporting beam by suitable bolts 26, the supporting beam therefor being provided with a series of suitably positioned apertures 27 to facilitate the adjustment of the legs thereon and longitudinally thereof so as to enable the user to arrange the form walls for the construction of thick or thin building walls, 90 as desired.

95 Each of the legs 25 of one beam, as for example, the beam 23, has an edge thereof provided with a lateral flange 28 each designed to oppose a similar flange 28 formed along one edge of the adjacent leg of the other beam.

100 As shown in Figures 6 and 8, one leg of one beam engages and is secured to one of the form walls 15 or 16 while the other leg there- 105 of engages and is secured to one of the walls 18 of the core structure so that a clear space is left between the walls of the core structure and the legs maintain all of the walls in the desired position so that cement may be placed between the inner and outer form walls and the core walls, as will be readily understood.

110 The type of form most frequently used is 115 illustrated in Figures 6 to 11, this type being employed for adding sections or units to the building wall after the first section has been formed. In this type the walls of the form do not extend to the bottom of the legs 25 but terminate a substantial distance thereabove and, as is shown in Figure 8, each leg carries upon the face of the flange 29, below the wall, 120 a rubber foot or button 25' which projects slightly beyond the plane of the wall face.

125 The rear ends of the beams 22 and 23 of each of the form wall holding members are ex- 130 tended and are connected together by means of an operating latch structure which in- 135 cludes an arm 30 pivotally attached at one end as at 31 to one of the beams and having pivotally attached thereto as at 32, inwardly of its pivot point 31, one end of a link 33

which has its other end pivotally attached as at 34 to the adjacent beam.

It will thus be seen that by swinging the arm 30 outwardly and upwardly the inner end of one of the beams will be swung up above the other beam thus causing the legs 25 thereof and the walls carried thereby to swing away from the legs and walls of the other beam so that the space between the opposing flanges of the legs of the two beams will be increased to permit the wall forms to be removed from position. It will, of course, be readily seen that a reversal of the operation of the latching structure between the beams 15 will bring the same back to parallel position so that the opposing walls carried by the flanges of the legs will be arranged in substantially parallel relation to maintain the form walls in place.

When the center two legs of each of the holding members are in position between the walls 18 of the core structure and the holding member latched in operative position, the resilient webs 20 between the core walls 18 will be expanded slightly so that when the form wall holding members are released these webs will contract and collapse the wall air space forming cores 17.

In order to prevent the weight of the cement collapsing the webs 20 between the walls 18 of each core structure there is provided a reinforcing structure which connects the adjacent ends of the core structures and holds the webs thereof rigid. This reinforcing structure is indicated as a whole by the numeral 35 and comprises a pair of planks 36 of substantially the same width as the webs 20 hingedly connected together at one end as at 37 by a suitable resilient material such as belting material or leather. At the other ends these planks are connected by a suitable latch 38, which is pivotally attached to one plank and has the other end turned for frictional engagement over the other plank as shown in Figure 9.

When the forms described are used for continuing the formation of a previously formed wall section they are so set-up upon the previous wall section as to arrange the lower edges of the walls 15, 16, and 18 upon the top of the previously formed wall, the rubber feet or buttons 25' engaging the adjacent face of the walls as shown in Figure 8.

The beams 22 and 23 are then brought into parallel relation in the manner previously described and held by swinging the latch arm 30 downwardly to the position shown in Figure 8. This action presses the feet or buttons 25' against the previously formed wall section thus holding the form securely in place.

The reinforcing structures 35 are then arranged in position so that one plank of each of these structures will overlie the inner face of a web 20, the structure straddling the space between the webs of the cores which

they connect, as shown in Figure 9. The upper ends of the planks are then drawn together and connected by the latch 38 so that the planks will be held in substantially parallel relation and will maintain the adjacent webs of the cores sufficiently rigid to prevent their collapsing when the cement is poured in between the walls and between the webs.

In starting the wall, forms of substantially the same construction as those shown and described are employed with the exception of the fact that the walls 15, 16, and 18 are continued downwardly to the ends of the legs 25 to which they are attached, the buttons 25' being, of course, done away with. Also, in the forming of the first wall unit the holding members 35 for the webs of the adjacent cores are put into place in inverted condition and the free lower ends are drawn together to proper position by passing wires about the planks below the hinge connection 27 therebetween. The cement is then poured to bring the height of the wall up to a point adjacent the wires connecting the members 35 and after the poured wall has been set the holding wires may be released and the reinforcing structures 35 removed with the form. In this manner a low starting wall may be formed, which wall is indicated by the numeral 39. From the foregoing description it will be readily seen that the form walls 15, 16 and 18 may be easily and quickly placed in the desired position upon a previously cast wall such as that indicated, and securely held in proper position thereon while cement is placed therein. After the cement has set release of the latch members 30 of the members 21 will permit easy removal of the forms from position.

It is, of course, obvious that the form will have to be used in a number of units and where the walls of the units come together a secure connection therebetween is obtained by providing an edge of each of the walls of one unit with an off-set portion 40 having a plurality of longitudinally extending apertures therethru, while the other side edge of said wall of the unit is provided with a series of outwardly projecting pins 41 which are adapted to enter the apertures of the off-set portion of the walls of the adjacent unit in the manner shown in Figure 12.

In the use of the building set described it is necessary that the brick forming structure be used in association with the wall forming structure for building operations as loose brick or broken brick is often needed to fill in partitions along small rooms or closets where the wall molding form cannot be employed. Therefore, it is desirable that these bricks and blocks be formed ready for use at the same time that the wall structure is cast and is setting.

Having thus described my invention, what I claim is:—

1. A mold for hollow structures comprising a form having outer walls, a core unit disposed between said outer walls including a pair of walls having permanently attached connecting elements of stretchable material therebetween permitting relative movement thereof, and a holding element maintaining said outer walls and said core walls in set position.
- 10 2. A mold for hollow structures comprising outer mold walls, a core body adapted to be disposed between the outer walls for the formation of a hollow center in the molded structure and comprising a pair of walls permanently joined at adjacent edges by walls of a character to have their surface areas changed with the shifting of the core walls relative to each other, and a holding element adapted to maintain the outer mold walls in spaced relation and to maintain the core walls spaced against the tension of said resilient connections.
- 15 3. A form structure for walls having hollow or celled centers comprising inner and outer form walls, core structures adapted to be disposed in spaced relation between said walls and each comprising a pair of wall members having permanent stretchable connecting walls between their side edges, means for maintaining said stretchable walls of adjacent core structures in a predetermined position relative to each other, and holding elements adapted to maintain the core walls in spaced relation against the tension of said resilient connections and to maintain the inner and outer walls in set position relative to the cores.
- 20 4. A mold form for walls, comprising connectable sections each including an inner and outer mold wall, core bodies disposed between said inner and outer walls and each including a pair of spaced walls and walls of stretchable material permanently connecting the end edges thereof, means for joining the resilient end walls of adjacent core ends to maintain the same against collapse, and means for joining and holding in predetermined relation the inner and outer mold walls and the core walls.
- 25 5. A mold form for walls, comprising connectable sections each including an inner and outer mold wall and a plurality of collapsible core bodies disposed between the inner and outer walls, each of said core bodies comprising a pair of spaced side walls and end walls of stretchable material permanently connecting the adjacent end edges of the side walls, said core bodies being disposed in spaced alignment, means for reinforcing and connecting the adjacent end walls of the spaced core bodies to maintain the latter against collapse, and elements maintaining the inner and outer mold walls and the walls of the core bodies in predetermined spaced relation comprising a pair of beams disposed transversely
- 30 of the walls, a pivotal connection between the beams, and a pair of legs carried by each of the beams, one of the legs of each beam carrying a core wall and the other leg of each beam carrying one of the other of the first mentioned walls.
- 35 6. A mold form for walls, comprising connectable units each consisting of an inner and outer mold wall and a plurality of collapsible cores disposed therebetween in spaced relation, each of said cores including a pair of spaced side walls and end walls of stretchable material permanently connecting the adjacent end edges of the side walls, holding elements joining the end walls of adjacent cores to maintain the same against collapse, and holding units maintaining the inner and outer walls and the core walls in predetermined spaced relation, each comprising a pair of beams disposed transversely of the tops of the walls, a pair of legs carried by one of said beams, one of said legs being secured to the outer wall and the other being secured to a core wall remote therefrom, a pair of legs carried by the other of said beams, one being secured to the inner mold wall and the other being secured to the core wall remote therefrom, and a pivotal connection between said legs whereby the beams and legs may be shifted to move a mold wall and a core wall remote therefrom from the other walls.
- 40 7. A mold form for walls, comprising connectable units each consisting of an inner and outer mold wall and a plurality of collapsible cores disposed therebetween in spaced relation, each of said cores including a pair of spaced side walls and end walls of stretchable material permanently connecting the adjacent end edges of the side walls, holding elements joining the end walls of adjacent cores to maintain the same against collapse, and holding units maintaining the inner and outer walls and the core walls in predetermined spaced relation, each comprising a pair of beams disposed transversely of the tops of the walls, a pair of legs carried by one of said beams, one of said legs being secured to the outer wall and the other being secured to a core wall remote therefrom, a pair of legs carried by the other of said beams, one being secured to the inner mold wall and the other being secured to the core wall remote therefrom, a pivotal connection between said legs whereby the beams and legs may be shifted to move a mold wall and a core wall remote therefrom from the other walls.
- 45 8. A mold form for walls, comprising an inner and outer mold wall, core members disposed between said inner and outer walls, in spaced relation permitting the formation of webs between the sections of the wall molded

between the outer wall and the cores and between the inner wall and the cores, each of said cores comprising a pair of spaced side walls and end walls of stretchable material permanently connected to and between the adjacent ends of the side walls, holding elements between the adjacent end walls of the cores, each comprising a pair of elongated bodies extending vertically through a core along the inner face of a resilient end wall, a hinge connection between the lower ends of said members and a latch connection between the upper ends of said members, and means connecting and holding the inner and outer walls and the core walls in a predetermined spaced relation.

9. A mold form for walls, comprising an inner and outer mold wall, core members disposed between said inner and outer walls in spaced relation permitting the formation of webs between the sections of the wall molded between the outer wall and the cores and between the inner wall and the cores, each of said cores comprising a pair of spaced side walls and end walls of stretchable material permanently connected to and between the adjacent ends of the side walls, holding elements between the adjacent end walls of the cores, each comprising a pair of elongated bodies extending vertically through a core along the inner face of a resilient end wall, a hinge connection between the lower ends of said members and a latch connection between the upper ends of said members, and adjustable means connecting and holding the inner and outer walls and the core walls in a predetermined spaced relation whereby the space between the inner and outer walls and the space between the core walls may be varied.

40 In testimony whereof I hereunto affix my signature.

ALBIN E. JURY.
